ADJUSTABLE SUPPORT STAND FOR AN ENGINE PERFORMANCE INSTRUMENT OR SIMILAR ARTICLE

Edwin L. Schwartz, Los Angeles, Calif., assignor to Rite Autotronics Corporation, Los Angeles, Calif.

Filed Dec. 12, 1974, Ser. No. 532,760

Term of patent 14 years

Int. Cl. D6—99

Fig. 1.

Fig. 3.

Fig. 2.

Fig. 5.

Fig. 4.

Fig. 6.

FIG. 1 is a front elevational view of an adjustable support stand for an engine performance instrument or similar article showing my new design, an instrument being fragmentarily depicted in broken lines for illustrative purposes only;

FIG. 2 is a top plan view taken from the top of FIG. 1;

FIG. 3 is a side elevational view taken from the right side of FIG. 1;

FIG. 4 is a bottom plan view;

FIG. 5 is a rear elevational view; and

FIG. 6 is a side elevational view taken from the left side of FIG. 1.

I claim:

The ornamental design for an adjustable support stand for an engine performance instrument or similar article, substantially as shown.
